(57) **CLAIM**

We claim the ornamental design for a control device, as
shown and described.

DESCRIPTION

FIG. 1 is a perspective view of a control device showing our
new design.

FIG. 2 is a front view thereof.

FIG. 3 is a left side view thereof.

FIG. 4 is a right side view thereof.

FIG. 5 is a top view thereof.

FIG. 6 is a bottom view thereof.

FIG. 7 is a perspective view of a control device showing a
second embodiment of our new design.

FIG. 8 is a front view thereof, left side, right side, top, and
bottom views, respectively, of the second embodiment being
identical to the left side, right side, top, and bottom views of
the first embodiment.

FIG. 9 is a perspective view of a control device showing a
third embodiment of our new design.

FIG. 10 is a front view thereof.

FIG. 11 is a left side view thereof.

FIG. 12 is a right side view thereof.

FIG. 13 is a top view thereof.

FIG. 14 is a bottom view thereof.

FIG. 15 is a perspective view of a control device showing a
fourth embodiment of our new design; and,

FIG. 16 is a front view thereof, left side, right side, top, and
bottom views respectively, of the fourth embodiment being
identical to the left side, right side, top, and bottom views of
the third embodiment.

The rear views form no part of the design and are omitted.
The surface shading indicates contour. The dashed broken
lines depict structure or features which form no part of the
claimed design. The dot-dash broken lines depict boundaries
which form no part of the claimed design.
